UNITED STATES PATENT OFFICE.

WILLIAM P. BETTENDORF, OF DAVENPORT, IOWA.

UNDERFRAME FOR CARS.

SPECIFICATION forming part of Letters Patent No. 780,317, dated January 17, 1905.

Application filed March 21, 1904. Serial No. 199,084.

To all whom it may concern:

Be it known that I, WILLIAM P. BETTENDORF, a citizen of the United States, and a resident of Davenport, in the county of Scott and State of Iowa, have invented certain new and useful Improvements in Underframes for Cars, of which the following is a full, clear, and exact description.

Economy of construction, ability to withstand the pulling strain and resist the concussion or shock of the bumping of the cars, and adaptability to maintain the standard distance of the draft-rigging above the rails are the essential considerations necessary to be observed in the building of the center sills of the underframes of ordinary cars. Heretofore such center sills have been made of continuous timber or beams extending from end to end of the car having specially-formed extremities and provided with special attachments for the draft-rigging or have been made of several spliced sections of timber or of metal beams having the draft-rigging attachments or drop-frames for said attachments connected thereto.

The object of my invention is to dispense entirely with said attachments, and thus avoid the shearing of rivets or bolts used in connection therewith, and to provide center sills which possess all the characteristics first mentioned to a maximum degree. This I accomplish by the novel means hereinafter described in the specification and fully set forth in the claims.

In the drawings, Figure 1 is a perspective view of one end of the underframe of a car embodying my invention, which is broken away from the remainder thereof. Fig. 2 is a perspective view of the same dismantled by having the high side sill and center sill removed. Fig. 3 is a similar perspective taken almost in side elevation. Fig. 4 is a plan view of the end portions of one of the center sills of my invention. Fig. 5 is a side view thereof, showing the body-bolster in cross-section. Fig. 6 is a perspective view of one end of my improved underframe looking toward the end of it.

Referring to the drawings, A A represent

the side sills, B the end sill, and C the body-bolster, of the underframe of a car. I prefer to make these parts of pressed steel and of rolled metal beams, although this is not essential. The body-bolsters are preferably provided with suitable end extensions *a*, that pass under and support the side sills. The center sills of this underframe between the bolsters is preferably made of sections of rolled-metal beams D D, which at a point near said body-bolsters are riveted or otherwise connected to the adjacent flanged shank *b b* of the cast-metal end extensions E E of said center sills. These extensions are constructed so as to pass over the bolster and are provided with recesses *c* in their lower edges, up into which said body-bolster enters. On either side of recess *c* the lower edges of these center sills are dropped to form shoulders *d d*, that abut against the sides of the bolster. Both the lower edge and upper edge of the extensions D are preferably flanged throughout their length, and the lower flanged extremities of shoulders *d d* thereof are provided with transverse grooves *e e*, into which the tenons *f f*, projecting up from the ends of the parallel members of the substantially H-shaped body center plate G, enter. Each of these parallel members of plate G pass transversely under the bolster and connect the lower extremities of the shoulders *d* of the metal ends D of the center sills, respectively, and rivets are preferably employed for this purpose. The cross member of said plate G has the usual center bearing-boss *n* depending down therefrom midway between the center sills, and it is provided with the necessary concentric opening for the passage of the king-bolt therethrough. As before stated, the edges of the ends E of the center sills are flanged laterally. This applies also to the edges of the recesses *c* therein, and the edge of said recesses above the bolster have lateral flanges *g*, which project to an extent corresponding to one-half the distance between said center sills and meet. These flanges *g* are preferably secured by riveting or otherwise to the upper flanges of the parallel I-beams composing the body-bolster C and are provided with corresponding semicircular re-

- cesses h in their meeting edges that together form the upper bearing for the king-bolt. The flanges i , projecting from the ends E opposite flanges g , also project farther from 5 that side of the extension than at other points along its length and are riveted to the upper flanges of the truss-beams of the body-bolster. In view of lines of strain to which the metal ends E will be subjected both above and 10 in front and to the rear of the body-bolster, I prefer to reinforce the same on both sides by a vest of horizontal ribs j and vertical and downwardly-inclined spreading ribs m , which latter converge toward a common center above 15 and in the same transverse plane as the king-bolt center and connect and merge into the upper and lower flanges of the said extensions E , as shown. Between the body-bolster and the end sill B the opposing sides of said extensions are provided with guideways or pockets o for the follower-plates of the draw-bar, substantially as shown. In order to effect the 20 distribution of the strain upon the extension imparted from the draft-rigging through the medium of the follower-plates, I prefer to advance the rectangular portions of the vertical web of said extensions forming the background of these guideways, to bound the top and the end walls of said guideways by laterally flanged or projected surfaces, and to provide the side of the extensions opposite said guideways with longitudinal ribs p . 25
- In view of the differently-constructed draft-riggings it is possible to use with my improved center sills I do not desire to be confined to the exact construction of the extensions E of the center sills as hereinbefore described or as shown in the drawings. It is obvious these cast-metal end extensions of the center sills 30 can be built lower down than as shown in the drawings when the height of the car-body requires it or can be built high, according as desired, without departing from the spirit of my invention.
- 40 45 What I claim as new is—
1. An under sill for a car comprising a rolled-metal beam terminating between the bolsters, and cast-metal ends therefor extending over the body-bolsters.
  2. An under sill for a car comprising a rolled flanged metal beam having cast-metal ends extending over the body-bolsters.
  3. An under sill for a car comprising a rolled-metal beam terminating between the body-bolsters of said car and cast-metal ends therefor which extend over the body-bolsters of said car.
  4. An under sill for a car comprising a rolled flanged metal beam having cast-metal ends which extend over the body-bolsters of said car.
  5. A center sill for a car having cast-metal ends which pass over the body-bolster of said car and extend to the end thereof in the same horizontal plane as said bolster and have the 65 attachments for carrying the draft-gear made in one piece therewith.
  6. A center sill for a car having cast-metal ends which have a recess in the lower edge thereof where they arch over the body-bolsters 70 of said car, and extend from thence to the ends of said car.
  7. A center sill for a car having cast-metal ends which have recesses in the lower edges thereof where they arch over the body-bolster of said car and extend from thence in the same horizontal plane as said bolster to the ends of said car and have the attachments for carrying the draft-gear made in one piece therewith. 75
  8. A center sill for a car comprising a rolled-metal beam and terminating between the body-bolsters and cast-metal ends which pass over the body-bolster of said car and extend in the same horizontal plane as said bolsters to the end thereof and have attachments for the draft-gear made in one piece therewith. 85
  9. A center sill for a car comprising a rolled-metal beam and terminating between the body-bolsters and cast-metal ends having a recess in the lower edges thereof where they arch over the body-bolsters of said car. 90
  10. A center sill for a car comprising a rolled-metal beam and terminating between the body-bolsters and cast-metal ends that are provided with recesses in their lower edges where they arch over the body-bolsters and have the attachments for the draft-gear made in one piece therewith. 95
  11. A center sill for a car comprising a rolled-metal beam and terminating between the body-bolsters and cast-metal ends which have recesses in the lower edges thereof where they arch over the body-bolster of said car and extend from thence to the ends of said car 100 and have the attachments for the draft-gear made in one piece therewith. 105
  12. A center sill for a car comprising a rolled-metal beam and terminating between the body-bolsters and cast-metal end extension therefor, the latter having a recess in its under edge where it arches over the bolster, and is provided with a downwardly-extending shoulder abutting against said bolster. 110
  13. A center sill for a car comprising a rolled-metal beam and terminating between the body-bolsters and cast-metal end extensions therefor, the latter having a recess in its under edge where it arches over the body-bolster of said car and has downwardly-extending shoulders on each side of said recess which abut against said bolster. 115
  14. A center sill for a car comprising a metal beam which terminates between the body-bolsters and cast-metal end extensions therefor which passes over the body-bolster 120
  15. A center sill for a car having cast-metal ends which pass over the body-bolster of said car and extend to the end thereof in the same horizontal plane as said bolster and have the attachments for carrying the draft-gear made in one piece therewith. 125

- of said car, and is provided with downwardly-extending shoulders which abut against both sides of said bolster.
15. A center sill for a car having alining cast-metal end extensions having recesses in their under edge where they arch over the bolster, and provided with downwardly-extending shoulders abutting against said bolster.
16. A center sill for a car having alining cast-metal end extensions having recesses in their under edges where they arch over the body-bolster of said car and have downwardly-extending shoulders on each side of said recesses which abut against said bolster.
17. A center sill for a car having alining cast-metal end extensions which pass over the body-bolster of said car, and are provided with downwardly-extending shoulders which abut against both sides of said bolster.
18. An underframe for cars comprising body-bolsters, center sills having cast-metal end extensions that pass over said bolster, and whose under edges above said bolster are provided with lateral flanges that meet mediate said sills, and are provided with a suitable king-bolt opening.
19. An underframe for cars comprising body-bolsters, center sills having cast-metal end extensions that pass over said bolster and whose under edges above said bolsters are provided with lateral flanges on both sides that are connected thereto, and between said sills meet and are provided with a king-bolt opening.
20. An underframe for cars comprising body-bolsters, center sills having cast-metal end extensions that pass over said bolster and are provided between their upper and lower edges with a series of laterally-projecting ribs above the same.
21. An underframe for cars comprising body-bolsters, center sills having cast-metal end extensions that pass over said bolster and are provided with a series of laterally-projecting horizontally-disposed and downwardly-inclined spreading ribs, above said bolster.
22. An underframe for cars comprising body-bolsters, center sills having cast-metal end extensions having recesses in their under edges where they pass over said bolster and are provided with a series of laterally-projecting ribs above the same between their upper and lower edges.
23. An underframe for cars comprising body-bolsters, center sills having cast-metal end extensions having recesses in their under edges where they pass over said bolster and are provided with a series of laterally-projecting horizontally-disposed and downwardly-inclined spreading ribs, above said bolster.
24. An underframe for cars comprising body-bolsters, center sills having cast-metal end extensions having recesses in their under edges where they pass over said bolster and are provided with a series of laterally-projecting horizontally-disposed and downwardly-inclined spreading ribs, above said bolster.
- edges where they pass over said bolster and 65 are provided with a series of laterally-projecting horizontally-disposed and downwardly-inclined spreading ribs, above said bolster and have downwardly-extending shoulders on each side of said recess that abut against said bolster.
25. An underframe for cars comprising body-bolsters, center sills having cast-metal end extensions having recesses in their under edges where they pass over said bolster and 75 are provided with a series of laterally-projecting ribs above the same and have downwardly-extending shoulders on each side of said recess that abut against said bolster.
26. An underframe for cars comprising 80 body-bolsters, center sills having cast-metal end extensions that pass over said body-bolsters and are provided with downwardly-extending shoulders on each side thereof that abut against the same, and means passing under said bolster and connecting said shoulders.
27. An underframe for cars comprising body-bolsters, center sills having cast-metal end extensions that are recessed where they pass over said bolsters and are provided with 90 downwardly-extending shoulders on each side thereof that abut against said bolsters, and means passing under the bolsters and connecting said shoulders.
28. An underframe for cars comprising 95 body-bolsters, center sills having cast-metal end extensions that pass over said body-bolsters and are provided with downwardly-extending shoulders on each side thereof that abut against the same, and a body center plate 100 connected to the lower extremities of said shoulders.
29. An underframe for cars comprising body-bolsters, center sills having cast-metal end extensions that are recessed where they 105 pass over said bolsters and are provided with downwardly-extending shoulders on each side thereof that abut against said bolsters, and a body-plate connected to the lower extremities of said shoulders.
30. An underframe for cars comprising body-bolsters, center sills having cast-metal end extensions that pass over said body-bolster and are provided with downwardly-extending shoulders on each side thereof that 115 abut against the same and have transverse grooves in their lower extremities, and a body center plate connected to said extremities and having tenons engaging the grooves therein.
31. An underframe for cars comprising 120 body-bolsters, and center sills having cast-metal ends that between said bolsters and the end of said car have integral guideways in the opposing surfaces thereof.
32. An underframe for cars comprising 125 body-bolsters, and center sills having cast-metal ends that pass over said bolsters and have integral guideways in the opposing sur-

faces thereof between said bolsters and the ends of said cars.

33. An underframe for cars comprising body-bolsters and center sills having cast-
5 metal ends that have recesses in the under edges thereof where they pass over the said bolsters and have integral guideways in the opposing surfaces thereof between said bolsters and the ends of the cars.
34. An underframe for cars comprising body-bolsters, center sills each consisting of a rolled-metal beam which terminates between said bolsters and cast-metal end extensions that arch over said bolster, and means for connecting the same thereto.
35. An underframe for cars comprising body-bolsters, center sills each consisting of a rolled-metal beam which terminates between said bolsters and cast-metal end extensions 20 that arch over said bolster, and integral means for connecting the same thereto.
36. An underframe for cars comprising body-bolsters, center sills consisting of a rolled-metal beam and having cast-metal end 25 extensions that pass over said bolster, and whose under edges above said bolster are provided with lateral flanges that meet mediate said sills, and are provided with a suitable king-bolt opening.
37. An underframe for cars comprising body-bolsters, center sills consisting of a rolled-metal beam and having cast-metal end extensions that pass over said bolster and whose under edges above said bolsters are provided with lateral flanges on both sides that are connected thereto, and between said sills meet and are provided with a king-bolt opening.
38. An underframe for cars comprising body-bolsters, center sills each consisting of a 40 rolled-metal beam which terminates between said bolsters and cast-metal end extensions that pass over said bolster and are provided with a series of laterally-projecting ribs above the same between their upper and lower edges.
39. An underframe for cars comprising body-bolsters, center sills consisting of a rolled-metal beam and having cast-metal end extensions that pass over said bolster and are provided with a series of laterally-projecting horizontally-disposed and downwardly-inclined spreading ribs, above said bolster.
40. An underframe for cars comprising body-bolsters, center sills each consisting of a 55 rolled-metal beam which terminates between said bolsters and cast-metal end extensions having recesses in their upper edges where they pass over said bolster and are provided with a series of laterally-projecting ribs above the same between their upper and lower edges.
41. An underframe for cars comprising body-bolsters, center sills consisting of a rolled-metal beam and having cast-metal end extensions having recesses in their under

edges where they pass over said bolster and are provided with a series of laterally-projecting horizontally-disposed and downwardly-inclined spreading ribs, above said bolster.

42. An underframe for cars comprising body-bolsters, center sills consisting of a 70 rolled-metal beam and having cast-metal end extensions having recesses in their under edges where they pass over said bolster and are provided with a series of laterally-projecting horizontally-disposed and downwardly-inclined spreading ribs, above said bolster and have downwardly-extending shoulders on each side of said recess that abut against said bolster.

43. An underframe for cars comprising 80 body-bolsters, center sills each consisting of a rolled-metal beam which terminates between said bolsters, cast-metal end extensions having recesses in their under edges where they pass over said bolster and are provided with a series of laterally-projecting ribs above the same and have downwardly-extending shoulders on each side of said recess that abut against said bolster.

44. An underframe for cars comprising 90 body-bolsters, center sills consisting of a rolled-metal beam and having cast-metal end extensions that pass over said body-bolsters and are provided with downwardly-extending shoulders on each side thereof that abut against the same, and means passing under said bolster and connecting said shoulders.

45. An underframe for cars comprising body-bolsters, center sills consisting of a rolled-metal beam and having cast-metal end extensions that are recessed where they pass over said bolsters and are provided with downwardly-extending shoulders on each side thereof that abut against said bolsters and means passing under the bolsters and connecting said shoulders.

46. An underframe for cars comprising body-bolsters, center sills consisting of a rolled-metal beam and having cast-metal end extensions that pass over said body-bolsters and are provided with downwardly-extending shoulders on each side thereof that abut against the same, and a body center plate connected to the lower extremities of said shoulders.

47. An underframe for cars comprising body-bolsters, center sills consisting of a rolled-metal beam and having cast-metal end extensions that are recessed where they pass over said bolsters and are provided with downwardly-extending shoulders on each side thereof that abut against said bolsters, and a body center plate connected to the lower extremities of said shoulders.

48. An underframe for cars comprising 125 body-bolsters, center sills consisting of a rolled-metal beam and having cast-metal end extensions that pass over said body-bolster

and are provided with downwardly-extending shoulders on each side thereof that abut against the same and have transverse grooves in their lower extremities, and a body center plate connected to said extremities and having tenons engaging the grooves therein.

49. An underframe for cars comprising body-bolsters, center sills each consisting of a rolled-metal beam which terminates between said bolsters, cast-metal ends that between said bolsters and the end of said car have guideways in the opposing surface thereof.

50. An underframe for cars comprising body-bolsters, and center sills each consisting of a rolled-metal beam which terminates between said bolsters, cast-metal ends that pass over said bolsters and have guideways in the

opposing surfaces thereof between said bolsters and the ends of said cars.

51. An underframe for cars comprising body-bolsters and center sills each consisting of a rolled-metal beam which terminates between said bolsters, cast-metal ends that have recesses in the under edges thereof where they pass over the said bolsters, and have guideways in the opposing surfaces thereof between said bolsters and the ends of the cars.

In testimony whereof I have hereunto set my hand this 9th day of March, 1904.

WILLIAM P. BETTENDORF.
